(57) **CLAIM**

The ornamental design for a bottle, as shown and described.

DESCRIPTION

FIG. 1 is a top, front and left side perspective view of the bottle according to my new design;

FIG. 2 is a top plan view thereof;

FIG. 3 is a right side elevational view thereof, the left side elevational view being a mirror image thereof; and,

FIG. 4 is a front elevational view thereof, the rear elevational view being a mirror image thereof.

The broken lines illustrate portions of the bottle that form no part of the claimed design.
